UNITED STATES PATENT OFFICE.

ALBERT HUGO FRIEDEL, OF CLEVELAND, OHIO.

PROPELLER.

No. 867,029.

Specification of Letters Patent.

Patented Sept. 24, 1907.

Application filed February 16, 1907. Serial No. 357,620.

To all whom it may concern:

Be it known that I, ALBERT HUGO FRIEDEL, a citizen of the United States, and a resident of Cleveland, in the county of Cuyahoga and State of Ohio, have invented a new and Improved Propeller, of which the following is a full, clear, and exact description.

This invention relates to certain improvements in propellers adapted for use in connection with water or aerial navigation, and relates more particularly to 10 means for supporting the propeller blades and varying the angle thereof in respect to the propeller shaft, whereby the speed of the vessel may be readily controlled or the direction reversed without the necessity of speed-changing reversing gears.

15 The invention consists in certain features of construction and combination of parts, all of which will be fully set forth hereinafter and particularly pointed out in the claims.

Reference is to be had to the accompanying drawings 20 forming a part of this specification, in which similar characters of reference indicate corresponding parts in all the figures, and in which

Figure 1 is a side elevation of one form of my improved propeller and operating mechanism connected thereto, a portion thereof being broken away; Fig. 2 is an end elevation of the parts shown in Fig. 1; Fig. 3 is a plan view of the reverse side of one of the propeller blades; Fig. 4 is an edge view of said propeller blade; Fig. 5 is a transverse section through one of the 30 propeller blade supports, said section being taken on the line 5—5 of Fig. 1; Fig. 6 is a central longitudinal section through the parts illustrated in Fig. 5; said section being taken on the line 6—6 of Fig. 5; Fig. 7 is a central longitudinal section through a portion of the 35 propeller shaft illustrating certain details of the controlling mechanism; Fig. 8 is a transverse section through the propeller shaft illustrating certain details of the controlling mechanism, said section being taken on the line 8—8 of Fig. 1; Fig. 9 is a side elevation of 40 a modified form of my invention; Fig. 10 is a side elevation of a further modification; Fig. 11 is a side elevation of another modification, portions thereof being broken away; Fig. 12 is a transverse section through the form illustrated in Fig. 11, said section being taken 45 on the line 12—12 of said figure; and Figs. 13 and 14 are edge elevations of modified forms of propeller blades.

In my improved propeller mechanism I provide a propeller shaft and a plurality of propeller blades operatively connected thereto, together with mechanism extending through the propeller shaft, whereby the inclination of the blades in respect to the shaft may be altered at will.

In the specific form of my invention illustrated in 55 Figs. 1 to 8, inclusive, I provide a hollow shaft 15 having any suitable mechanism (not shown) applied to

one end thereof for rotating the same. The outer end of the shaft is provided with hollow divergent arms 16 adapted to support the propeller blades. As illustrated, I provide only two of these arms, but it is evident that 60 any number desired may be employed. Each of the arms is preferably elliptical in cross section as illustrated in Fig. 5, and adjacent the outer end of each arm the side portions are cut away to separate the two side members and form extensions 17 and 18. From 65 the point upon the shaft 15 at which the arms 16 diverge, I provide a pointed end 19 extending back to a distance substantially equal to the length of the arms, whereby any resistance which otherwise might be caused by the action of the water against the square 70 end of the shaft is eliminated. For rigidly supporting the arms at the proper angle, I provide an annular ring 75 20 unattached to the pointed end 19 but rigidly secured to both of the arms, thus serving to not only prevent outward movement of the arms but also serving to prevent lateral movement of one in respect to the other. For further bracing the arms I provide a rod or wire 21 preferably connected to one of the extensions 17 and 25 passing through or in engagement with the pointed end 19 to the extension 17 of the opposite arm.

Supported by the arms and movable in relation thereto I provide a plurality of propeller blades 22 of any suitable form or size and having means for pivotally connecting the same to the ends of the extensions 17 and 18. In the form illustrated in Figs. 1 to 4, inclusive, this pivotal connecting means comprises two lugs 23, 23 having perforations therethrough for the passage of a suitable bolt or pivot pin. As will be noted, the ends of the extensions 17 and 18 lie in the same radial line from the propeller shaft, and the propeller blades 90 therefor remain at a constant radial angle to said shaft, but as the extension 18 is preferably somewhat longer than the extension 17 and as the propeller blades are pivotally connected to the ends of both of the extensions, the inclination of said blades in respect to the 95 axis of the propeller shaft may be varied at will. For controlling the movements of these blades I provide means connected to the blades at one or more points and extending through the arms and propeller shaft to the interior of the vessel.

100 Various forms of controlling means may be employed, but in Figs. 1 to 8, inclusive, I have illustrated this means as including a plurality of wires or cables 24. These wires or cables 24 extend in pairs through the propeller shaft, and each pair leads through a separate arm to one of the propeller blades. As shown, each arm adjacent the base of the extension 17 and 18 is provided with a cross partition 25, whereby the entrance of water to the interior of the arm is effectively prevented, and adjacent each end of this partition I provide openings 105 for the passage of the wires or cables. Each propeller blade is provided with suitable openings or rings 26,

whereby the cables may be attached to the propeller blades, and these rings or openings are preferably disposed upon opposite sides of the two lugs 23. From these connecting rings the cables extend between the 5 two arms to the partition 25, at which point each wire or cable is provided with a smooth elongated collar or sleeve 27 slidably mounted within the openings in said partition. These sleeves or collars are rigidly secured to the cables and closely fit the openings, whereby 10 upon the longitudinal movement of the cables the collars slide through the openings and maintain at all times a practically water-tight joint therewith. In Fig. 6 I have illustrated the two sleeves or collars in the position which they would occupy when the propeller blades are inclined to the position illustrated in dotted lines in Fig. 1.

Each pair of cables extends from its corresponding propeller blade through the supporting arm therefor and through the propeller shaft to a point within the 20 interior of the vessel, as previously stated. Within the vessel suitable means are provided for simultaneously drawing upon one of the cables of each pair and loosening the other, whereby all of the propeller blades may be simultaneously inclined in the proper 25 direction. For accomplishing this end, I provide the mechanism illustrated in Figs. 1, 7 and 8, which mechanism comprises a collar 28 slidably mounted upon the propeller shaft 15 and having a groove 29 in its outer circumference for the engagement of a suitable yoke 30. This yoke is mounted upon a suitable pivot pin 31 and is adapted to be moved longitudinally of the shaft by any suitable handle 32. The shaft 15 is provided with openings in the walls thereof adjacent the collar 28, whereby the cables 24 may pass to the exterior 35 of the shaft, and the collar 28 is provided with openings 33 for the passage of the cable therethrough. Adjacent the collar 28 I provide a collar 34 rigidly secured to the shaft and provided with small pulleys 35, the number and location of said pulleys corresponding 40 with the number of cables and the location of the openings 33 within the collar 28. The ends of the cables 24 extend through the wall of the shaft and through the collar 28 and are united around the pulley 35, whereby a longitudinal movement of one cable causes a simultaneous 45 longitudinal movement in the opposite direction of the other cable of the same pair. One of each pair of cables is rigidly secured within the collar 28 by suitable means, as, for instance, a set screw 36, whereby the longitudinal movement of the collar in 50 respect to the shaft causes one of each pair of cables to move therewith. In this manner by moving the handle 32 in one direction, I cause such an inclination of the blades as would cause a forward movement of the vessel, while by moving the handle 32 in the opposite 55 direction the position of each controlling blade is reversed.

In the specific form of my invention above described, I employ two or more propeller blades arranged concentric to the shaft and all at equal distance therefrom, 60 but it is evident that the propeller blades may be arranged at varying distances from the shaft, as, for instance, in two concentric circles. In Fig. 10 I have illustrated a modified form of my invention in which two sets of arms 16^a and 16^b are employed for supporting 65 two concentric sets of propeller blades 22^a and 22^b op-

erated by cables in any suitable manner, as, for instance, that illustrated in Figs. 1 to 8, inclusive.

In the form of my invention illustrated in Figs. 1 and 10, the propeller blades are supported from the side facing toward the front of the vessel, but it is evident that 70 the propeller blades may be supported from the opposite side if desired. In Figs. 9 and 11 I have illustrated a modified form in which the arms 16^a supporting the propeller blades, are curved to a semi-circular form, so as to present the smooth face of each propeller blade to 75 the direct current of the water or air against which said blade operates. These propeller blades are illustrated as being pivotally supported and operated in the same manner as is the propeller blades illustrated in Figs. 1 and 10. 80

It is evident that instead of employing cables or wires for operating the blades suitable rods may be employed, and in Figs. 11 and 12 a form employing such rods is illustrated. In this form I provide the shaft 15 with forwardly-extending and divergent arms 16^d, to the 85 ends of which the blades 22^d are pivotally connected, but instead of providing cables through the shaft 15 and arms 16^d I provide in the former two semi-cylindrical rods 37, 37^a lying side by side and longitudinally movable. At the inner end of each rod I provide connecting rods 38 extending through the arms 16^d and pivotally connected to the propeller blades. These rods may be connected to the longitudinally movable rods 37 in any suitable manner, whereby upon the longitudinal movement of said rods the connecting rods are 90 caused to impart motion to the propeller blades. In order that the propeller blades may be inclined in the same direction simultaneously, it is necessary that two of the connecting rods shall cross as indicated in Fig. 12, and to permit of this I preferably extend a portion 100 of one of the rods 37^a to a somewhat greater distance than the other rod 37, and to this longer rod I connect the longest of the connecting rods, namely, 38^a. Any suitable means may be employed for moving the rods 37, 37^a simultaneously in opposite directions, whereby 105 as one side of each propeller blade is drawn toward the end of the shaft 15, the opposite side of the propeller blade is drawn away to produce the desired inclination. In case connecting rods are employed rather than cables or wires, it may be found that the propeller blades 110 will be supported rigidly enough if only a single rod be connected to each one, in which case the blade would be operated in one direction by pulling down said rod, and operated in the opposite direction by a pushing action. In such a case only one connecting lug 26^a 115 will be employed; as illustrated in Fig. 13.

Instead of connecting the extensions 17 and 18 to lugs or ears 23 as above described, it is evident that the ends of said extensions may be inserted within recesses or openings in the propeller blade 22^a and fastened 120 thereto by pivot pins, as illustrated in Fig. 14. In this figure I have also illustrated the cables 24 as being secured within openings in the blade rather than as being connected with links or rings 26 as illustrated in Figs. 3 and 4. 125

The propeller above described is especially designed for use in connection with engines or other prime movers which are non-reversible and run at a constant speed, but it is evident that it may be used with a reversible engine or one having a reversing and speed 130

changing gear, in which case the propeller blades might be rigidly connected to the ends of the arms and the operating rods or cables entirely omitted.

Having thus described my invention, I claim as new 5 and desire to secure by Letters Patent:

1. A device of the class described, comprising a hollow shaft, hollow rearwardly-extending arms rigidly secured thereto, propeller blades pivotally connected to the outer ends of said arms, and means extending through said shaft 10 and said arms for simultaneously varying the inclination of each of said blades.

2. A device of the class described, comprising a propeller shaft, rearwardly-extending divergent arms secured to said shaft, propeller blades adjustably secured to the ends 15 of said arms, and means for adjusting the inclination of said propeller blades.

3. A device of the class described, comprising a propeller shaft, rearwardly-extending arms rigidly secured to said shaft, each of said arms having a plurality of divergent 20 extensions, and propeller blades pivotally connected to said extensions.

4. A device of the class described, comprising a hollow propeller shaft, hollow divergent arms extending outwardly

therefrom, propeller blades pivotally connected to the outer ends of said arms, a plurality of controlling means 25 extending through said shaft and through each of said arms and connected to said blades, and means carried by said shaft for operating said controlling means.

5. A device of the class described, comprising a hollow shaft, a propeller blade pivotally supported adjacent the 3 end thereof, a plurality of cables extending through said shaft and operatively connected to said blade, and means for pulling upon either of said cables for varying the inclination of the blade in respect to the shaft.

6. A device of the class described, comprising a propeller 35 shaft, a plurality of rearwardly-extending divergent arms carried thereby, means connecting said arms but independent of said shaft for supporting and bracing the former, and propeller blades secured to the outer end of each of said arms.

In testimony whereof I have signed my name to this specification in the presence of two subscribing witnesses.

ALBERT HUGO FRIEDEL.
